UNITED STATES PATENT OFFICE.

FREDERICK E. GROUT AND CHARLES B. GROUT, OF ORANGE,
MASSACHUSETTS.

DESIGN FOR A VEHICLE-FRAME.

SPECIFICATION forming part of Design No. 31,803, dated November 7, 1899.

Application filed September 21, 1899. Serial No. 731,227. Term of patent 14 years.

To all whom it may concern:

Be it known that we, FREDERICK E. GROUT and CHARLES B. GROUT, citizens of the United States, and residents of Orange, Franklin county, State of Massachusetts, have invented and produced a new and original Design for Motor-Vehicle Frames, of which the following is a specification, reference being had to the accompanying drawings, forming part there-
of, in which—

Figures 1, 2, and 3 represent a side, plan, and end view, respectively, of a motor-vehicle frame embodying our new design.

As shown in the drawings, the leading or material feature of our design consists of a frame having oppositely-located sides 1 1, each being formed with two pieces 2 2 extending substantially parallel with each other

throughout the greater portion of their length and terminating at opposite ends of the frame 20 in rounded loops 3 3, one of which latter encloses or contains a vertically-elongated opening 4 and the other a substantially circular opening 5. Between the sides 1 1 extend cross-braces 6 6 6, two of which at the forward end 25 of the frame support a bearing-clip 7.

Having thus described our invention, what we claim as new, and desire to secure by Letters Patent, is—

The design for a vehicle-frame, substantially as herein shown and described.

FREDERICK E. GROUT.
CHARLES B. GROUT.
